UNITED STATES PATENT OFFICE

ERNEST A. GOSNELL, OF WICHITA FALLS, TEXAS, ASSIGNOR TO PANHANDLE STEEL PRODUCTS COMPANY, OF WICHITA FALLS, TEXAS

TUBING AND ROD MACHINE

Application filed September 16, 1927. Serial No. 220,017.

My invention relates to oil well machinery, and it has for its object the production of an improved device for pulling or lowering tubing and rods from and into oil wells more quickly and in a more efficient manner than has heretofore been possible. Specific objects of the invention are to make the machine light, easily operated and easily transported, so that it may be moved over ordinary ground and roads with ease from point to point of use, without cumbersome material, capable of doing anything that any other mast or pulling machine will do, with greater ease, and to work successfully with any tractor and winch. Other objects will sufficiently appear from the detailed description herein-after.

I attain my object by making a telescopic mast of metal tubing, the lowermast carrying a pair of traction wheels and having a base structure formed in inverted Y-shape to permit the operator to see through to the work.

My invention is illustrated in the accompanying drawings, in which

Fig. 1 is a side view of the mast set up and in operation;

Fig. 2 is a view at right angles to Fig. 1 with the winch and the hauling parts omitted;

Fig. 3 is a side view of the machine dismounted and swung into a horizontal position on its chassis ready for transportation;

Fig. 4 is a side view of the topmast (fore-shortened) and the upper part of the lowermast (in section) showing their interconnection and mode of relative travel.

Referring to the drawings, and particularly to Figs. 1 and 2, 1 is the lowermast, 2 is the topmast telescoping therein, and 3 is the base frame with the horizontal base member 4. All these members, 1, 2, 3 and 4 are tubular and the parts 1, 3 and 4 are welded together so as to form a rigid integral unitary structure. The lowermast 1 is preferably provided with footholds 5 and also with horizontal openings 6 through which the bolt or pin 7 may be inserted to support the topmast 2 in any position desired (see Fig. 4). The base tube 4 carries eyes 8 by means of which it may

be chained to stakes, or if desired as shown in Fig. 1 secured to railroad irons or the like embedded in the earth. At its upper end the lowermast 1 carries a collar 9 permanently shrunk, welded or otherwise rigidly secured thereto. At one side, with its axis parallel to the base member 4, is a sheave 10 journaled in ears 11 on the collar 9. A hoisting rope 12 passes over this sheave and down inside the lowermast to the foot of the topmast where it is secured as shown in Fig. 4 to be presently described. Eyes such as 39 for guys are on four sides of the collar.

Approximately midway of the length of the combined structure I secure upon the lowermast a chassis composed of side frame members 13, cradle member 13^a and cross member 14, carrying the axle 15 upon which are secured the wheels 16. The frame members 13 are secured to the cradle by bolts 17, and the cradle upon the mast by yokes 18 or equivalent devices. It will be noted that the axle 15 lies in a plane parallel to the base member tube 4, and this arrangement has a definite purpose, in that it brings the base tube horizontal when the wheels are on the ground, and also permits the base tube to be dropped on the ground in setting up the device, secured in place and thereafter hoisted by means of a single guy, the other guy ropes serving merely to steady it.

The Y-shaped arrangement at the base is constructed specifically in that manner for the purpose of allowing the man operating the tractor and winch to see exactly what is going on in front of him, in lowering into the well or pulling out of the well tubing and rods, and the top of the inverted Y must be high enough to enable the tractor operator to view the work in front of him. This feature or perfection in the base and Y to the practical operator means a great deal, in that it improves and quickens the work to be done.

A further point in this arrangement is the following: By preference I employ a tractor 19 fitted with a power take-off and a winch 20, and means for coupling it to the mast for transportation. In setting up the mast, the tractor is available, by backing off to raise the mast, the base tube 4 having been dropped

and secured to stakes in the ground, and the guy 21 or equivalent being applied to the winch. Other means may be employed to raise the mast, so that I am not confined to this arrangement, but it makes for efficiency and economy.

The topmast 2 carries at its upper end a shackle or clevis 22 pivoted on a bolt 23 (Figs. 1 and 4) extending through the head of the mast. To this clevis is attached the end of the hoisting line 24 which passes down over the traveling pulley 25, then up over the fixed sheave 26 and then down as a hauling part to the winch 20. It should be here observed that instead of passing directly to the winch, the hauling part 24 may go through a fixed sheave at the foot or base of the mast in order to change direction of the haul for the winch. The weight of the tractor however would ordinarily be sufficient to balance the weight of tubing being pulled, and this might be multiplied if desired between the clevis 22 and the traveling pulley 25 by connecting another pulley to the clevis, and then multiplying the number of sheaves in both pulleys so as to increase the number of turns or parts of the rope 24 between them.

The fixed hoisting sheave 26 is journaled on a bolt or axle 27 passing through a yoke 28 having side parts 29—30 extending down opposite sides of the head of the mast and bolted or riveted thereto as shown at 31. The yoke or strap 28 being thus of inverted U-shape, carries in its upper part a closed housing 32 constituting an inverted semi-circular trough over the sheave, with eyes 33—34 formed at its two opposite extremities for attachment of the guy ropes 21 and 35. Other guys 36—37 are attached to eyes on the collar 9 at the head of the lowermast 1, and these are the lateral guys, which supplement lateral resistance of the base member 4 in keeping the mast erect in the desired vertical plane. The guys 21 and 35 however are adapted to sway the mast back and forth into various positions in this plane, as required to exert a vertical pull upon the tubing 38 to be removed from the well which is secured to the traveling pulley 25 by means of the yoke 39 in a well understood manner. In addition to the eyes 33—34 or in place of the same, I may also employ a crown piece with eyelets 41—42 secured at the top of the yoke 32 for top guy wires. This is a detail which is sometimes important in practice but it will be understood that this and other features are subject to variations and modifications without departure from the invention.

Referring to Fig. 3, the entire mast is shown in horizontal position resting on the cradle 13^a supported by chassis members 13—14 on the axle 15 of the wheels 16. The base member 4 of the standard frame 3, being parallel to the axle 15 lies horizontal and the two sections of the mast are telescoped to

gether. In this position of the parts, the apparatus is ready for moving.

Referring to Fig. 4, the lowermast 1 is provided with the openings 6 already described for insertion of the bolt or pin 7 to maintain the topmast in any adjusted position. The topmast 2 runs through the collar 9 and at its lower end carries a support 43, which I have shown as a casting in the form of a solid flanged cap with a plug entering the lower end of the mast 2. This casting 43 has a fork 44 adapted to straddle the pin 7 in position, so as to maintain the sheave 26 in the proper plane, by holding the mast 2 against turning. Any equivalent arrangement may be substituted for the cap or plug 43 without departing from my invention.

The operation of my device thus described is as follows: Proceeding from one location to another, the apparatus is telescoped and lowered into a horizontal position as shown in Fig. 3. The base member 4 then furnishes a convenient means for handling the device, or for attaching it to a tractor. When going into operation, the base 4 is lowered to the ground, upon which it rests throughout its length. The eyes 8 are then secured by chains or otherwise to stakes or irons in the ground guy ropes are attached, and the mast is turned on the base 4 as a pivot, by hauling on the rear guy rope 21 in any desired manner. When the mast is in the position shown in Fig. 1 the guys are secured, and the hauling part of the rope 12 is attached to the winch and the topmast raised thereby to the desired height, after which the bolt or pin 7 is inserted beneath the footstep block 43, through the openings in the lowermast, and the apparatus is ready for operation. In this connection it should be noted that Figs. 1 and 2, while showing the mast in position for operation do not show the topmast hoisted up as it would be in practice, because of the limitation in size of a Patent Office drawing. It will be understood that the topmast 2 can be raised to any desired height by hauling on the rope 12, which of course is usually done before the tubing 38 is attached.

Particular points of advantage in this design of a pulling mast are, first, the arrangement and method of support of the lowermast, by which it is accurately and easily aligned with respect to the well, and given extended support; second, the provision of the chassis, whereby the structure may be moved on its own wheels, said wheels and the base structure being permanently related so as to automatically bring the mast in position for hoisting when it is lowered from the wheels, and automatically bring it in position on the wheels when it is lowered from hoisting; thirdly, the arrangement and relation of the parts so that the mast is maintained rigidly in one plane, but is movable in said plane, with its sheaves and other con-

nected parts, and finally, the arrangement of the open or Y shaped base so that the operator can see through and know what he is doing at all times.

5 It should be noted that the openings 6 in the mast 1 are reinforced at 6^a with plate which may conveniently be of dimensions 2 $\frac{1}{2}$ " x 2" x $\frac{1}{2}$ ". These plates are welded or otherwise secured to the metal of the mast.

10 What I claim is:

1. In a tubing and rod machine, a mast composed of tubular metal telescopic sections, the lower section being formed in inverted Y-shape, with a straight body member, two oppositely inclined side members and a transverse base member, all integrally welded together, the upper mast section being a straight tube telescoping within the body of the lowermast, with means to hoist the 15 upper mast partly out of the lowermast, means to lock the same when hoisted, and a pulling sheave mounted on the top of the upper mast.

2. The tubing and rod machine described 20 in claim 1, with the additional element of a wheeled truck comprising a pair of structural frame members rigidly and permanently secured to the straight body member of the lowermast, and a pair of wheels supported on said frame on a common axis parallel to the axis of the transverse base member of the Y.

3. The tubing and rod machine described in claim 1, with means maintaining the axis 25 of the pulling sheave at all times parallel with the axis of the truck and the axis of the tubular base member.

4. The tubing and rod machine described in claim 1, together with means for anchoring 30 the base tubular member adjacent to the point of work, and means for raising and lowering the entire mast around the axis of the tubular base member.

5. The tubing and rod machine described 35 in claim 1, with the additional elements of a power winch located on the opposite side of the mast from the point of work, with a hoisting rope having its hauling part connected to said winch and passing up over 40 the pulling sheave and then down vertically above the point of work, said winch and said hoisting rope being so arranged as to leave the Y base of the mast always open and clear of obstruction so that the operator may 45 observe the work therethrough.

6. The tubing and rod machine described 50 in claim 1, with locking means for the upper mast comprising a transverse bar passing through opposite openings in the lowermast 55 and reenforced bearing means for said bar.

7. The tubing and rod machine claimed in 60 claim 1, with locking means for the upper mast comprising a transverse bar extending through openings in opposite sides of the 65 lowermast and plates of metal welded to the

wall of the lowermast beneath the respective openings, so as to reenforce the same.

In testimony whereof I hereunto affix my signature.

ERNEST A. GOSNELL.
